UNITED STATES PATENT OFFICE.

CLAUDE H. McCUTCHEON, OF KITTANNING, PENNSYLVANIA, ASSIGNOR TO PITTSBURGH PLATE GLASS COMPANY, A CORPORATION OF PENNSYLVANIA.

APPARATUS FOR FORMING CLAY POTS.

Application filed December 1, 1921. Serial No. 519,266.

To all whom it may concern:

Be it known that I, CLAUDE H. McCUTCHEON, a citizen of the United States, and a resident of Kittanning, in the county of Armstrong and State of Pennsylvania, have made a new and useful invention in Improvements in Apparatus for Forming Clay Pots, of which the following is a specification.

10 The invention relates to apparatus for making of clay pots and particularly those employed in making plate glass, which are of the largest size and present the greatest obstacles to production by any process 15 except the ordinary hand methods which are tedious and expensive. It has for its main objects the provision of an improved apparatus, (1) whereby pots of large size may be made from ordinary pot clay by a 20 pouring or molding action; (2) whereby this result may be secured without the necessity of making the walls of the molding receptacle of plaster, and without the necessity of using a clay having a high mixture 25 degree of fluidity; (3) and whereby a uniform and sufficient amount of compacting or pressing force is applied to the clay so that the resulting pot is without voids, is of uniform density and composition, and in 30 general has the physical characteristics necessary to give a length of service comparable to that of the hand made pot. One type of construction for carrying out the invention is illustrated in the accompanying 35 drawings, wherein:

Figure 1 is a vertical section through the apparatus preferably employed with the sections constituting the side walls of the mold or receptacle in open position. Fig. 2 is a section on the line II-II of Fig. 1. Fig. 2 is an enlarged sectional detail. Figs. 3 and 4 are views similar to Figs. 1 and 2 but with the side sections of the mold in closed position. Fig. 5 is a vertical section 45 through the mold in a plane different from that of Fig. 3 to illustrate the locking keys for securing the side sections of the mold to the bottom and top or closure sections. Fig. 6 is a partial side elevation of the 50 receptacle to show the locking keys in end elevation. And Fig. 7 is an end view on a scale larger than that of the other figures, of one of the liners.

Briefly stated, the apparatus preferably 55 employed in carrying out the process com-

prises a fixed plunger for forming the interior surface of the pot and a receptacle for forming or shaping the outside of the pot, which receptacle is movable relative to the plunger in two directions, the bottom 60 of the receptacle and the side walls being movable vertically, while the side walls which are in sections, are movable horizontally so as to approach the side walls of the plunger. In carrying out the process 65 the clay to be compacted is placed in the receptacle beneath and around the plunger, after which the compacting action occurs, this being accomplished by moving the bottom of the receptacle upward and at the 70 same time moving the sides of the receptacle laterally. In this way two compacting effects are secured, the clay beneath the plunger being forced up against the end 75 and the clay at the sides of the plunger being forced against it laterally. The process whereby these two compacting movements are secured is most conveniently carried out by the apparatus illustrated, but other equivalent forms of apparatus 80 might be used to secure the same results. It is more feasible to make the receptacle collapsible and movable toward the plunger, maintaining the latter in fixed position, but the same result would be secured by a reverse 85 relative movement involving a movable plunger with the parts thereof capable of expansion and contraction, or by dividing these movements between the receptacle and plunger, the only requirement in so far 90 as the process is concerned being the vertical movement of the approach between the bottom of the receptacle and the plunger and the lateral movement of approach between the side walls of the receptacle and 95 the peripheral wall of the plunger, these two movements of approach preferably occurring simultaneously, although this is not essential.

Referring to the drawings, 1 is the core 100 which is carried by the spider 2 bolted at its ends to the four vertical T bars 3 3 3 3. The bottom 4 of the mold receptacle is carried by a plunger 5 working in a cylinder 6. Fluid pressure is applied 105 through the pipe 7 from the cylinder 8, in which works the plunger 9 operated from the pump handle 10.

The side walls of the receptacle comprise 110 the four parts 11 11 11 11, such parts being

shown in open position in Figs. 1 and 2, the spaces between the opposing edges of the sections being covered by the metal liners 12 12 12 12. These metal liners are preferably of the tapering form illustrated in Fig. 7, the edges being made relatively thin and sharp so that they may slide over each other when the side walls are collapsed. The side walls are made to move inward upon the upward movement of the bottom 4, such inward movement being secured by the use of the opposing sets of cam members 14, 15 and 16, 17, the cam members 14 and 16 being carried by the side sections 15 of the mold and the cam members 15 and 17 being carried by the vertical T bars 3. There are two of the cam members 14 and two of the cam members 16 on each of the side sections 11 and one each of the cam members 15 and 17 on each of the T bars 3, the cam members 15 and 17 being long enough to engage two of the cam members 14 or 16, as indicated in Fig. 2. When the bottom of the receptacle is moved upward to the position indicated in Fig. 3, the side sections 11 are cammed in to the positions indicated in Figs. 3 and 4.

A top or closure 18 is provided upon the upper edge of the side sections in order to prevent the upward escape of the clay when compression is applied by the relative movements of the core and receptacle, such top or closure being made in four sections corresponding to the side sections 11. In order to secure the side members 11 slidably to the bottom 4 and top 18, the key construction shown in Figs. 5 and 6 is preferably employed. The keys 19 and 20 are dovetailed into the side sections and into the top and bottom members so that the side sections can go laterally or horizontally toward and from the core, but at the same time any vertical movement between the side sections and the top and bottom are prevented.

In order to support the pot after the side sections are moved out and thus prevent breakage incident to moving or handling while the clay is still soft, the hoops 21 extending around the liners are employed. These hoops lie in grooves in the walls of the side sections with their ends overlapping opposite the slots 22 provided in the side sections as shown in Fig. 2^a. Collars 23 fit around the overlapped ends and are provided with clamping screws 24.

In carrying out the operation the spider 2 with its plunger 1 are removed to permit the ready filling with clay of the lower portion of the receptacle, such clay being in a very plastic condition but not having the same degree of fluidity as that which is used in the ordinary pot pouring operation. The spider with its core is then positioned and additional clay filled in around the sides

thereof. The closure sections 18 are then applied so that the parts occupy the position illustrated in Figs. 1 and 2. The hydraulic pump is now operated to apply pressure to the plunger 5, which causes the receptacle 70 carried thereby to move upward, so that compacting pressure is simultaneously applied between the bottom 4 of the receptacle and the bottom of the core and between the side walls 11 and the side walls of the core, 75 the side sections 11 being cammed inward as the receptacle moves upward. The top sections 18 prevent the escape of the clay upward from the top of the mold, so that any desired degree of pressure may be applied to the clay, thus eliminating voids and bringing the pot to a uniformly compacted condition. The ends of the hoops 21 are clamped together so that the pot will be supported by the liners 12 after the removal of the sections 11. After the pot has been formed and the clay allowed to set, the bottom 4 is allowed to move back to the position indicated in Fig. 1, the core is removed, and the side sections 11 taken off. 90 The pot, supported by the liners, may now be carried away for drying, seated upon the bottom 4, which bottom, with its plunger 5, is removed bodily from the apparatus upon a suitable truck. Or, if desired, the bottom 4 may be detached from the plunger 5 in order to move the pot, a new bottom member being secured in position upon the plunger for the succeeding operation.

If desired, this method of procedure may 100 be somewhat modified and the filling may be carried out without removing the core. In filling in accordance with this method the top sections 18 would be drawn back and the clay necessary to form the complete 105 pot filled in between the side walls of the receptacle and the core, tamping being applied to the extent necessary to cause the clay to flow laterally and fill the space between the bottom of the core and the bottom 110 of the receptacle. After the filling operation the procedure followed would be the same as that above described. It is also feasible when the filling is done with the core 1 removed, to put in the entire amount of clay 115 necessary to form the pot before putting the core in position, no filling being done after the core is in position.

What I claim is:

1. In combination in apparatus for forming clay pots, a base plate, a plurality of side wall members mounted slidably on the base plate for radial movement, a downwardly extending core in the upper portion of the cavity formed by the side wall members, a framework for holding the core against upward movement, power means for moving the base with the side wall members thereon upward, and cooperating means on the framework and side wall members for 130

causing an inward movement of said members when such side members are moved upward by said base plate.

2. In combination in apparatus for forming clay pots, a base plate, a plurality of side wall members mounted slidably on the base plate for radial movement, a downwardly extending core in the upper portion of cavity formed by the side wall members, a framework for holding the core against upward movement, power means for moving the base with the side wall thereon upward, and cooperating means in the framework and side wall members for causing an inward movement of said members when such side wall members are moved upward by said base plate, the said side wall members, core and framework being mounted in knock-down relation, so that after the pot is formed, said members and core may be removed to permit of the removal of the bottom plate with the pot supported thereon.
3. In combination in apparatus for forming clay pots, a receptacle for shaping the exterior of the pots, having side walls made

in parts and collapsible radially, a core for shaping the interior of the pots, means for giving a relative vertical movement to the receptacle and core, means for forcing the parts comprising the side walls of the receptacle inward, and a closure means secured upon the upper ends of said side walls with slide connections and fitting around the core.

4. In combination in apparatus for forming clay pots, a receptacle for shaping the exterior of the pots, having side walls made in sections and collapsible radially, liners inside the section bridging the spaces between the sections, releasable securing means around the liners for holding them in position on the pot and supporting it after the sections are removed, a core for shaping the interior of the pots, and means for forcing the sections inward to compact the clay around the core.

In testimony whereof, I have hereunto subscribed my name this 7 day of November, 1921.

CLAUDE H. McCUTCHEON.
